UNITED STATES PATENT OFFICE.

MYRON DINGS, OF MILWAUKEE, WISCONSIN.

MAGNETIC SEPARATOR.

1,349,501.

Specification of Letters Patent. Patented Aug. 10, 1920.

Application filed August 2, 1918. Serial No. 247,917.

To all whom it may concern:

Be it known that I, MYRON DINGS, a citizen of the United States, residing at Milwaukee, county of Milwaukee, and State of Wisconsin, have invented new and useful Improvements in Magnetic Separators, of which the following is a specification.

My invention relates to improvements in magnetic separators with particular reference to the so-called cross conveyer type of separator, in which the material to be separated is conveyed in one direction into a magnetic field and the magnetizable portion lifted from the conveying means and carried transversely to a magnetically neutral zone at one side thereof, where the lifted material is allowed to drop into a hopper upon a receiving conveyer, the residue on the main conveyer passing directly through the magnetic field to another point of delivery.

In the magnetic separators of this type as heretofore manufactured, the capacity of any given unit is limited, and the units are also limited in size by the quantity of suspended magnetite which can be carried by the upper or transversely moving conveyer without interfering with the movement of the non-magnetic material carried by the main conveyer. It is well known that the particles of magnetite tend to adhere to the cross conveyer and to each other in the form of so-called tresses, the particles first lifted becoming magnetized by induction, and attracting other particles thereto, whereby a series of particles hang suspended one from another. The cross conveyer therefore tends to become quickly over-loaded in such a manner as to obstruct the movement of material carried by the main conveyer, and also tends to mechanically sweep some of the non-magnetic material transversely of the conveyer, and delivering it into the hopper intended to receive the magnetite only, thus contaminating the magnetic product.

The object of my invention is to provide means for freely unloading the cross conveyer at predetermined points along the line of its travel across the main conveyer, and in such a manner as to effect a definite separation of the magnetite from the non-magnetic material in a series of successive loading and unloading operations performed by any given portion of the cross conveyer while traveling across the main conveyer.

In this manner, I propose to increase the capacity and size of my improved magnetic separators to any desired extent.

Another object of my invention is to provide a cross conveyer which will not sag or get out of shape, but which can be formed of material of minimum thickness having a perfectly even smooth surface all in one plane, whereby extremely delicate adjustments are possible, and whereby the dimensions of the air gaps may be reduced to a minimum. Where cross conveyers of the belt type are used the necessity for frequently renewing the belts causes considerable expense, delay and trouble. Such belts must of necessity be quite thick to obtain such strength to resist sagging strains, splicing joints, or repair joints, reduce irregular thick ends and uneven surfaces which are very detrimental to perfect working conditions. I have discovered that my objects can be best attained by employing a revolving disk composed of fabric stretched upon a circular hoop under sufficient tension to support it in a true horizontal plane. This fabric when so used may comprise very thin material, and the surface thereof may be kept smooth and even by the tension.

A further object of my invention is to increase the durability of the cross conveyer by providing a sectionalized magnetic field having arcuate pole pieces or members arranged at different distances from the center of the revolving conveyer, whereby the load upon the conveyer is distributed along both radial and circular lines, and whereby the wear is reduced to a minimum. Further, my object is to provide means whereby the separated materials, magnetizable and non-magnetic, are all delivered at the rear end of the main conveyer into a series of receivers provided for that purpose.

In the drawings:—

Figure 1 is a plan view of my improved magnetic separator, illustrating only the working elements, the frame being omitted.

Fig. 2 is a front elevation of the same, showing the main conveyer and the revolving cross conveyer in transverse section, drawn to a plane cutting the center of the cross conveyer.

Fig. 3 is a sectional view, drawn on line 3—3 of Fig. 1.

Fig. 4 is a detail view of the upper magnet, as seen from the under side.

Like parts are identified by the same ref-

erence characters throughout the several views.

An electro magnet 1, the winding 2 of which is illustrated in section in Fig. 3, is provided with a set of pole pieces 4 and 5 at its respective ends. An induced magnet 7 is superposed, and is provided at its end with the depending pole pieces which are preferably formed with a series of arcuate ribs 9 and 10, each of which is curved in an arc, described substantially from the center of the magnet 7. This center is located in a vertical line drawn through the center of the revolving cross conveyer hereinafter described.

I preferably arrange the arcuate members or ribs 9 and 10 in pairs at different radial distances from said vertical center line as best shown in Fig. 4, and as also indicated by dotted lines in Fig. 1. All of these ribs, however, directly overhang the pole pieces 4, and constitute polar projections into which the magnetic lines of force are concentrated, by reason of the reduced dimensions of the magnetic gap between the lower edges or margins of these ribs and the pole pieces 4.

A main conveyor belt or apron 12 extends through the magnetic field at the respective ends of the magnets 1 and 7, and travels over supporting drums 13 and 14 at the front and rear ends respectively. The material to be separated is delivered to this belt through a hopper 15, which has a plurality of feed openings 16 in the bottom, (Fig. 1), spaced apart for a purpose which will now be explained.

It will be observed, (Fig. 2) that the apron 12 is subdivided into longitudinally extending bands by providing the outer surface with thickened strips 18 having raised marginal portions or ribs 19, thereby forming shallow troughs 20 extending longitudinally of the apron, and separated by intervening troughs 21, the bottoms of which comprise the thinner portions of the apron.

Immediately above the apron and between it and the magnet 7 a non-magnetic disk 25 is mounted to revolve upon a central axis co-inciding with the central vertical line above referred to. This disk is preferably composed of fabric, and its margins are secured to a circular rim 27, preferably formed of wood. The fabric is tightly stretched in all directions, whereby it may be held by the rim in a true horizontal position. The outer portions of the rim is provided with a circular band 29, (preferably metallic) supported by ball bearings 30 from a suitable raceway 31. This rim is actuated, from any suitable source of power, by a set of rollers 33 mounted upon vertically disposed actuating shafts 34, and rotated in frictional contact with the peripheral margin of the rim.

The hopper 15 is arranged with its openings or feed slots 16 in position to discharge

the material to be separated into the troughs 20 of the main conveyer in the form of a thin sheet or screen of material. The main conveyer carries this material through the magnetic field between the pole piece 4 of electromagnet 1 and the arcuate ribs 9 and 10 at the front end of magnet 7. The magnetizable material is lifted from the trough 20 by magnetic attraction, and held in contact with the moving surface of the rotating disk 25 while such surface is in the magnetic field established by the pole piece ribs 9 and 10. But as soon as the material attracted by any one of these ribs 9 or 10 is carried beyond the rib into the succeeding gap between it and the next set of ribs, such material is allowed to drop into the trough 21 of the main conveyer which registers with such gap. The cross conveyer 25 is therefore unloaded at this point, and is ready to receive additional magnetizable material when crossing a subsequent magnetic field. By staggering the sets of ribs 9 and 10, as above described, I avoid reloading the same portion of the conveyer 25 while crossing each successive trough 20 on the main conveyer. The second load will be received at either a greater or a less distance from the center of the cross conveyer, and both the strain and the wear will therefore be distributed.

At the rear or discharge of the main conveyer, I provide a set of hoppers or receiving slides 35, each alternate hopper or slide 35 being in a position to receive material from a main conveyer trough 20, while the intermediate hoppers or slides receive the separated magnetizable material from the troughs 21.

It will, of course, be understood that all of the material in the troughs 20 is subjected to magnetic force by a second set of pole pieces after passing the center line of the machine, the magnets being provided with polar projections at each end, similarly grouped and arranged as above described with reference to the front end of the machine. The specific arrangement of the magnets is, however, not essential to my invention. I have not shown means for adjusting the magnets and conveyers, this being deemed unnecessary for the reason that such adjusting mechanism is common in the art, and it will be assumed by those skilled in this art that adjustments will be provided for wherever desired.

I claim:

1. In a magnetic separator, an electromagnet having stationary attracting polar projections subdivided into short sections, disposed in a series transverse to the line along which the material travels, and having each projection in the series also disposed transversely to said line, and separated from the other projections by non-magnetic gaps.

2. In a magnetic separator, an electromagnet having polar projections each subdivided into short sections of like polarity, and separated from each other by non-magnetic gaps, 5 in combination with a conveyer subdivided into bands with alternate bands disposed for registry with the pole piece sections and intermediate bands disposed for registry with the gaps between them.
- 10 3. In a magnetic separator, an electromagnet having polar projections each subdivided into short sections of like polarity, and separated from each other by non-magnetic gaps, in combination with a conveyer 70 subdivided into bands with alternate bands disposed for registry with the pole piece sections and intermediate bands disposed for registry with the gaps between them, and means, carried by the conveyer, for 75 separating material on the bands which traverse the magnetic gaps from the intermediate bands which cross said polar projections.
4. A magnetic separator having a stationary magnetic field subdivided and spaced to 80 form a line of short zones of attraction of like polarity, separated from each other by non-magnetic zones, in combination with a conveyer adapted to feed material through 85 said zones transversely of said line, and another conveyer for magnetized material adapted to feed such material along said line, whereby the material is discharged in alternate non-magnetic zones.
- 35 5. A magnetic separator having a magnetic field subdivided and spaced to form fixed zones of attraction of like polarity separated by non-magnetic zones, in combination with means for conveying material in a 90 plurality of thin streams through said magnetic fields, and a cross conveyer adapted to carry the attracted material laterally into the non-magnetic zones.
6. In a magnetic separator, a traveling 95 conveyer subdivided longitudinally into ribbon-like strips upon which material is carried, and having intervening ribs or walls to prevent mechanical distribution of material from one strip to another.
- 50 7. In a magnetic separator, a moving conveyer subdivided longitudinally into ribbon-like strips, having intervening ribs or walls to prevent mechanical distribution of material from one strip to another, and means 100 for magnetically lifting material from one strip, and then depositing it upon an adjacent strip.
8. In a magnetic separator, a moving conveyer subdivided longitudinally into ribbon-like strips, having intervening ribs or walls to prevent mechanical distribution of material from one strip to another, means for magnetically lifting material from one strip, and then depositing it upon an adjacent 105 strip, together with a set of receiving hoppers at the delivery end of the conveyer, each adapted to receive the material from one of the strips.
9. In a magnetic separator, a conveyer subdivided longitudinally into ribbon-like strips, having intervening ribs or walls to prevent mechanical distribution of material from one strip to another, means for magnetically lifting material from one strip, and then depositing it upon an adjacent 110 strip, together with a set of receiving hoppers at the delivery end of the conveyer, each adapted to receive the material from one of the strips, and a feeding hopper adapted to deliver material to be separated 115 upon alternate strips.
10. In a magnetic separator, a conveyer comprising a circular piece of fabric, in combination with a ring with which the margins of the fabric are connected under tension, sets of antifriction devices supporting 120 said ring, and a rotary member adapted to engage the periphery of the ring to actuate the same.
11. In a magnetic separator, a conveyer 125 for magnetizable material comprising a thin disk having its margin connected with a non-yielding ring under tension.
12. In a magnetic separator, the combination of a conveyer, a stationary magnet having segmental pole pieces, each extending in a general direction transverse to the conveyer, and a co-operating stationary magnet having opposing pole pieces of opposite polarity, subdivided into a series of short attracting sections, each disposed along lines generally transverse to the conveyer and in a series which extends transverse to the conveyer above a polar segment of the first 130 mentioned magnet.
13. In a magnetic separator, a stationary electro-magnet having polar projections subdivided into short sections, and separated from each other by non-magnetic gaps, in combination with a conveyer having bands 135 substantially equal in width to the length of said sections, and adapted to convey material through the magnetic fields established by said sections, said conveyer having intervening pads in registry with said non-magnetic gaps, and means for mechanically transferring the attracted material magnetically lifted from the first mentioned bands to the bands in registry with said gaps.
14. In a magnetic separator, the combination with a conveyer subdivided longitudinally into a series of bands, and having divisional projections along the margins of said bands, of an electro-magnet having polar projections in proximity to alternate 140 conveyer bands, said polar projections comprising short sections disposed along lines obliquely transverse to the bands, and mechanical means operating between said polar projections and bands to remove material 145 150

4
magnetically lifted from the alternate bands and disposed upon the intermediate bands, said polar projections having gaps between them corresponding substantially to the width of the intermediate bands.

15. In a magnetic separator, a conveyer for magnetizable material comprising a thin disk substantially impervious to said mate-

rial, said disk having its margins connected under tension with a rigid ring. 10

In testimony whereof I affix my signature in the presence of two witnesses.
